UNITED STATES PATENT OFFICE.

FREDERICK J. STERNER, OF BALTIMORE, MARYLAND.

RAILWAY-CHAIR.

No. 881,737.

Specification of Letters Patent. Patented March 10, 1908.

Application filed June 10, 1907. Serial No. 378,070.

To all whom it may concern:

Be it known that I, FREDERICK J. STERNER, a citizen of the United States, residing at Baltimore, in the State of Maryland, have 5 invented certain new and useful Improvements in Railway-Chairs, of which the following is a specification.

This invention relates to improvements in railway chairs, and has for its object to provide a device for rigidly supporting the ends 10 of the rails, thereby preventing vibration, and consequently crushing of the ends of the rails.

My invention further contemplates a device by means of which the ends of the rails 15 may be more securely fastened and prevented from spreading.

Other features of my invention will be more fully set forth in the following specification and pointed out in detail in the claims.

In the accompanying drawing,—Figure 1 is a side elevation of the outside of the rail showing my invention applied thereto. Fig. 2 is a side elevation of the inside of the rail. 25 Fig. 3 is a side elevation of the outside of the rail, the chair being removed, and showing the ends of the rails cut away at their outside lower flanges. Fig. 4 is a vertical sectional view through a point where the rails join.

Referring to the accompanying drawings, forming part of this specification, and in which like reference numerals designate like parts throughout the several views thereof, 1 designates the chair which is formed with a 30 flat base 2 of sufficient length to rest upon at least three of the cross-ties, and is provided at its center with a vertical projection 3, which latter is provided with a number of apertures 4. The chair is counter-sunk in 35 the ties upon which it rests to a depth sufficient to allow its upper surface to be on a line with the upper surface of the other ties. The lower flanges of the rails 5 are cut away at their abutting ends, as at 6, on the outside 40 of the rail sufficiently to allow the projection 3 of the chair to fit into said cut out portion. The said lower flanges of the rail are cut off on a vertical line with the outside of the upright portion 7 of the rail and the projection 45 3 of the chair fits against the flat surface 8 formed by cutting off said flanges. The outer edge of the base 1 is of the same contour as the portion of the rail cut away. The ends of the rails are provided with apertures 50 corresponding in number to the number of apertures 4 in the projection 3, through

which bolts 10 pass. Thus it will be seen that the said projection 3 also takes the place of one of the fish plates usually used to connect the rails. The inside lower flange of 60 the rail is provided with apertures adapted to register with a corresponding number of apertures in the base 2, through which bolts 11 pass. Thus it will be seen that the ends of the rails coming together over one of the 65 cross-ties, and being bolted to the vertical projection 3 and the base 2, it will be impossible for the ends of the rails to vibrate or to spread. The chair may be spiked to the ties 70 on both sides.

Having thus described my invention, what I claim is:

1. The combination with the rails having their outer lower flanges cut away at the ends 75 of a rail chair comprising a base upon which the rails rest and a vertical projection adapted to fit into the cut out portion of the rails.

2. The combination with the rails having their outer lower flanges cut away at the ends 80 of a rail chair comprising a vertical projection adapted to fit into the cut out portion of the rails and a base upon which the rails rest and having its ends projecting beyond the said vertical projection.

3. The combination with the rails having their outer lower flanges cut away at the ends, 85 of a rail chair comprising a base of sufficient length to rest upon at least three of the cross-ties and upon which the rails rest and a vertical projection adapted to fit into the cut out portion of the rails and having its upper edge impinging against the lower surface of the head of the rail and provided with a plurality of apertures.

4. The combination with the rails having their outer lower flanges cut away at the ends and provided with apertures above said cut away portion, of a rail chair having a base upon which the rails rest and projecting beyond the cut-away portion and a vertical projection adapted to fit into the cut out ends of the rails, having its upper edge impinging against the lower surface of the head of the rails and provided with a number of apertures, and bolts passing through the said vertical projection and rails.

5. The combination with the rails having their outer lower flanges cut away at the ends and provided with apertures above said cut away portion and a number of apertures in their lower inner flanges, of a rail chair hav-

ing a base upon which the rails rest and projecting beyond the cut away portion of the rails and having a number of apertures to register with the apertures in the lower inner flanges of the rails and a vertical projection adapted to fit into the cut out portion of the rails and having a number of apertures therein, bolts passing through the lower rail

flanges and the base, and bolts passing through the vertical projection and rails. 10

In testimony whereof I affix my signature in presence of two witnesses.

FREDERICK J. STERNER.
